UNITED STATES PATENT OFFICE.

ALFRED J. FLAUDER, OF BRIDGEPORT, CONNECTICUT, ASSIGNOR TO THE WEIDLICH BROS. MFG. CO., OF BRIDGEPORT, CONNECTICUT, A CORPORATION OF CONNECTICUT.

DESIGN FOR A SALT AND PEPPER SHAKER.

Application filed December 30, 1922. Serial No. 4,770. Term of patent 7 years.

To all whom it may concern:

Be it known that I, ALFRED J. FLAUDER, a citizen of the United States, and a resident of Bridgeport, in the county of Fairfield and State of Connecticut, have invented a new, original, and ornamental Design for Salt and Pepper Shaker, of which the following is a specification, reference being had to the accompanying drawing, forming a part thereof, and in which—

Fig. 1 shows a top plan of a salt and pepper shaker embodying my design;

Fig. 2 is a side elevation of the same; and Fig. 3 is a further elevation showing the two sides opposite those shown in Fig. 2.

I claim:

The ornamental design for salt and pepper shaker substantially as shown.

Signed at Bridgeport, in the county of Fairfield and State of Connecticut, this 27th day of December, A. D. 1922.

ALFRED J. FLAUDER. [L. S.]
